UNITED STATES PATENT OFFICE.

SAMUEL L. WORSLEY, OF BUFFALO, NEW YORK, ASSIGNOR TO PLUMB,
BURDICT & BARNARD, OF SAME PLACE.

MACHINE FOR THREADING SCREWS.

SPECIFICATION forming part of Letters Patent No. 232,869, dated October 5, 1880.

Application filed March 1, 1879.

To all whom it may concern

Be it known that I, SAMUEL LORD WORSLEY, of Buffalo, in the county of Erie and State of New York, have made a new and useful invention of Improvements in Machinery for Screwing or for Threading Bolts, some of which are applicable to other purposes; and I do hereby declare that the following is a full, clear, and exact description and specification of the same.

The principal object of the invention is to take bolts automatically, one at a time, from a bolt-holder, to cut screw-threads upon their stems, and to discharge them from the machine. The cutting of the screw-threads, commonly called the "screwing" or "threading" of the bolt, is effected by holding it stationary while a screw-die is simultaneously revolved and advanced upon the bolt-point; and after the screw-thread is cut to the requisite extent the revolution of the screw-die is reversed so as to back it off the bolt-point. Hence the screw-die is caused to revolve in alternately opposite directions, and the duration of the period of direct movement previous to reversal determines the extent of the screw-thread formed upon the bolt-stem. It is, however, expedient that the same machine should be capable of being used to cut screw-threads of different extents upon bolts; and to this end the object of some of the improvements hereinafter described is to vary the periods of reversal of the movement of the revolving shaft or mandrel carrying the screw-die as required to form screw-threads of different extents—that is, screw-threads making different number of turns around the bolt-stems.

The said improvements consist of various combinations of devices, of which devices the following are the principal, viz: Gripers or jaws by means of which the bolt-blank is held stationary during the threading or cutting of the screw-thread upon its stem; a die holder or chuck by which the screw-die is held and moved; a revolving sliding mandrel by which the die-holder and die are turned and caused to advance against the bolt-blank so as to cut the screw-thread thereon; revolving gearing by which the mandrel is caused to revolve in either of two directions; reversing-gearing by

means of which the direction in which the mandrel is caused to revolve is reversed; a leading-cam, or some equivalent or substitute therefor, to commence the advance of the screw-die upon the bolt-blank, or vice versa; 55 variable-pawl change-gearing by means of which the times at which the reversing-gear reverses the direction of movement of the revolving mandrel can be varied without necessarily removing parts of the machine and substituting others in their places, and without dependence upon the longitudinal movement of either the die-holder or the grippers which hold the blank to be threaded; a bolt-holder in which bolt-blanks ready for screwing or 60 threading are held; a bolt-mover by means of which the bolt-blanks are taken one at a time from the bolt-holder; one or more stops by which the descent of bolt-blanks in the bolt-holder is checked when the lowest bolt-blank 65 is to be taken by the bolt-mover; transfer fingers or mechanism by means of which a bolt-blank is transferred from the bolt-mover to the grippers or jaws by which the bolt-blank is held during screwing or threading.

Sundry minor devices, hereinafter particularly described, are also employed in making some of the combinations claimed as the invention. The said devices are combined by combining mechanism the construction and 80 character of which can be varied as circumstances render expedient, or to suit the views of different constructors.

In order that the invention may be fully understood, I have represented in the accompanying drawings, and will proceed to describe, the principal parts of a bolt-threading machine embodying my improvements in the best form in which they have been embodied at this date.

Figure 1 of said drawings represents a plan 90 of the said machine. Fig. 2 represents a front elevation of the same. Fig. 3 represents an end view of the same. Fig. 4 represents a transverse section of the machine at the line xx of Fig. 1. Fig. 5 represents a transverse 95 section of the machine at the line yy of Fig. 1. In some of said figures certain parts are omitted for perspicuity. Figs. 6 to 16 represent views of detached parts of the machine, designated by the same letters as the same parts 100

are designated by in the other figures, and some of said parts being represented upon a larger scale than in the other figures.

The working parts of said machine are connected with a strong frame, A, and all the moving parts derive their motion from a driving-shaft, B, which is held in suitable bearings of that frame, and is fitted with a belt-pulley, C, to which the driving-belt is applied.

10 In practice it is convenient either to apply a movable tightening-pulley to the driving-belt, so that the latter can be slackened and the machine stopped by moving the tightening-pulley, or to apply a loose pulley to the driving-shaft, and to employ a belt-shipper to transfer the belt to and from the driving-pulley and this loose pulley.

15 The driving-shaft B is connected, by means of cog-gearing, hereinafter more particularly described, with a counter-shaft, B', a clutch-shaft, B², and a revolving hub, B³, the last being mounted upon a cam-shaft, B⁴.

20 The bolt-blank to be screwed or threaded is held during threading between a pair of grippers or jaws, D D, which grasp its shoulder beneath the bolt-heads and hold the bolt-blank stationary, or so that it cannot revolve. When a square or angular shouldered bolt-blank is to be threaded the adjacent faces of the jaws 25 are constructed with angular grooves fitting the angular shoulders of the bolt-blanks.

25 The screw-die by which the screw-thread is cut is held by a die-chuck, E, which is secured to the mandrel F. This mandrel is con-

30 nected by cog-wheels a a' with the clutch-shaft B², and is also supported in boxes b b, which permit it to revolve and to slide endwise toward and from the jaws D D. The axis of this mandrel and the axial line of the opening of 35 the jaws are in the same straight line, so that when the bolt-blank is held in the jaws it is in line with the axis of the screw-die carried by the die-chuck E of the revolving mandrel F.

35 In order that the jaws D D may gripe the bolt-blank and may release it, they are pivoted in an opening of the jaw-standard b' of the main frame, so that they may open and close like pinchers. In the working machine the jaws are closed and are permitted to open by means 40 of a slide, which is connected by toggle-links with their shanks, and the slide is operated by means of a cam which is secured to the cam-shaft B⁴, and is connected with the slide by means of a lever. A spring also is employed 45 to move back the slide whenever the gripping-jaws are to be opened.

50 As no claim is made to any novelty in the means for opening and closing the jaws D D, and as the means above referred to are in common use for operating the jaws of other kinds of screw machinery, and as a representation of such means in the drawings would increase their complexity, it has been deemed better to omit the representation of such means from 55 the drawings.

60 As before stated, the mandrel F is connected

by means of cog-gear a a' with the clutch-shaft B², so that it is caused to revolve by the action of the clutch-shaft. The die-mandrel F and clutch-shaft must, however, be caused to revolve in alternately-opposite directions to cause the die to cut the screw-thread and to back off of the bolt after the screw-thread is cut. In order that the said devices may be revolved alternately in opposite directions while the driving-shaft B continues to revolve in the same direction, the clutch-shaft is connected with the driving-shaft by means of revolving gearing, as follows: Two cog-wheels, a² and a³, are mounted upon the clutch-shaft B², with the capacity to turn freely upon it. One of these cog-wheels, a², is connected directly with a cog-wheel, a⁴, secured to the driving-shaft B. The other cog-wheel, a³, of the clutch-shaft is connected with an intermediate cog-wheel, a⁵, secured to the counter-shaft B', which is caused to revolve in the opposite direction to the driving-shaft by the action of the cog-wheel a⁶ 80 upon that intermediate cog-wheel, a⁵. Hence the clutch-wheels a² a³ are caused to revolve 85 continuously in reverse directions, and the connection of the clutch-shaft B² with one or other of said clutch-wheels causes the clutch-shaft B², the mandrel F, and the die connected therewith to revolve either forward, as indicated 90 by the arrow in Fig. 1, or backward. The clutch-wheels and cog-wheels thus described constitute the revolving mechanism by which the mandrel is caused to revolve in either of 95 two directions.

100 In order that the clutch-shaft B² may be connected with the clutch-wheels a² a³ alternately, the clutch G is provided. This clutch is fitted to slide longitudinally upon the clutch-shaft, but is compelled to turn with it by means of a feather and groove, and its heads are fitted with clutch-teeth arranged in suitable positions to engage with corresponding teeth protruding from the adjacent faces of the clutch-wheels. The clutch is shifted upon the clutch-shaft to engage with one or other of the clutch-wheels by means of a double-graded cam, d, which is secured to the counter-shaft B' and operates upon the movable pins e e' of a shifting carriage, d'. This carriage is arranged to slide 115 upon a bar, d², parallel with the clutch-shaft, and is connected with the clutch G by a fork, d³, which fits in a circular groove of the clutch-body. The shifting-pins e e' are fitted to slide up and down in sockets of the shifting carriage, 120 and whenever either pin is dropped downward in its socket its point is engaged by the shifting-cam d, and the clutch is shifted by the action of that cam, the cam-grade e², Fig. 16, and pin e operating to shift the clutch into connection with the clutch-wheel a³, and the cam-grade e³, Fig. 16, and pin e' operating to shift the clutch into connection with the clutch-wheel a². The clutch, the shifting-pins, and the shifting-cam thus effect the reversal of the movement of the mandrel, and constitute the reversing 125 gearing or mechanism of the machine.

In order that the shifting-pins c c' may be raised and dropped automatically, two cams, c^4 c^5 , are provided, and each of these pin-cams is caused to operate upon its appropriate pin by means of a lever, c^6 and c^7 , and a link, c^8 and c^9 . The pin-cams c^4 c^5 are secured to the shaft B^5 , which is constructed to revolve in bearings secured to the main frame, and the revolution of the shaft causes the protuberances of the cams to raise and to drop the pins as required. When the clutch G is in gear with either clutch-wheel a^2 or a^3 the mandrel F and the die carried by it will continue to revolve in the same direction until the clutch is shifted. The length of time during which the mandrel and die continue to revolve in the same direction should, however, be capable of variation, to adapt the machine to cutting screw-threads having a different number of turns upon the bolt, or extending different lengths along the bolt-shank.

In order that the pin-cams c^4 c^5 may be operated automatically, but may at the same time have their operation varied to change or vary the times of shifting the clutch, their shaft B^5 is not connected with the driving-shaft by means of invariable combining mechanism, but is connected therewith by means of the following variable-pawl change gearing or mechanism: A ratchet-wheel, H , is secured to the end of the shaft B^5 , which carries the pin-cams c^4 c^5 , and a vibrating pawl, h , is provided to operate upon this ratchet-wheel. The shank of the lever h' of the vibrating pawl is connected by a link, h^2 , with a crank-pin, h^3 , whose shank is secured in a groove which extends radially across a hub, h^4 , secured to the counter-shaft B' , so that the crank-pin is adjustable toward and from the axis of the counter-shaft which carries it. The continuous rotation of the counter-shaft B' turns the crank-pin h^3 and causes the pawl h to vibrate at every revolution; but the extent to which the pawl vibrates, and consequently the amount of movement which it imparts to the ratchet-wheel H , to the change-gear shaft B^5 , and to the pin-cams c^4 c^5 secured thereto, depends upon the position in which the adjustable crank-pin h^3 is secured in the groove of the hub h^4 . If the adjustable crank-pin be close to the center of the hub, the vibration of the pawl is sufficient to move the ratchet-wheel H but one tooth at a time. Hence under this adjustment of the crank-pin the change-gear shaft B^5 and the cams c^4 c^5 will be turned slowly, and the clutch-shaft, mandrel, and die will run for a comparatively long period in one direction before being reversed. By shifting the position of the adjustable crank-pin h^3 in the groove of the hub h^4 the extent of movement of the pawl h is varied, and it may be made to vibrate to the extent of two, three, or four teeth of the ratchet-wheel, in which cases the latter, the change-gear shaft B^5 , and the pin-cams c^4 c^5 will be turned faster, and the clutch will be shifted at shorter intervals,

corresponding with the cutting of screw-threads, making a less number of turns upon the bolt-shank.

In order that the adjustable crank-pin may be readily shifted or adjusted in the groove of the hub h^4 , the crank-pin is in the present example constructed with a tubular body or journal traversed by a screwed stem, having at its inner end the shank which fits in the dovetailed groove of the hub and at its outer end a screw-nut, which is slackened to permit the crank-pin to be adjusted and tightened to secure the adjustable crank-pin in its place. The same result of varying the extent of movement of the pawl may be accomplished by providing the hub h^4 with a series of holes at different distances from the center of the counter-shaft, and by shifting the crank-pin from one hole to another.

85

In practice it is generally sufficient to have a machine capable of four variations or changes of the operation of the reversing-gearing, and consequently the present machine is fitted to vary the vibration of the pawl h from one to four ratchet-teeth. If a greater number of vibrations of the same extent are required, the pawl h must be made capable of a greater extent of vibration; or, if the vibrations are to be made less in extent, the ratchet-teeth must be made shorter, or the pawl and teeth may be replaced by a vibrating clamp operating upon a wheel-rim, like the means employed to operate the feed-wheels of sewing-machines. The variation of the movement of the pawl or clamp may, if preferred, be effected by shifting the lever-pin h^5 of the link h^2 radially of the pawl-lever h' , in place of shifting the crank-pin h^3 radially of the counter-shaft; but I prefer the latter modification. The ratchet-wheel or clamp-wheel, the variable pawl or clamp, and the adjustable crank-pin, or its substitute, by which the extent of movement of the pawl or clamp is varied, constitute the variable-pawl change-gearing of the machine.

110

When the mandrel F and the screw-die carried by it are turned in the direction to cut the screw-thread they must be advanced to the bolt-blank endwise thereof, and must be pushed against it sufficiently to start the cutting of the thread; or, in place of advancing the mandrel, the gripping-jaws, while holding the bolt-blank from turning, may be arranged to slide, and thus advance the bolt-blank to the screw-die. After the cutting is thus commenced the progressive formation of the screw-thread by the screw-die will draw the latter with the mandrel forward as long as the turning of the mandrel in the advancing or cutting direction is continued, and thus cause the screw-thread to be cut to the requisite extent. In order that the cutting of the screw may be started, the mandrel F and the screw-die are advanced or moved longitudinally toward the grippers or jaws D D by means of a leading-cam, I . This leading-cam I is secured to the cam-shaft B^4 , and its cam-grade i , Fig. 9, operates upon the

- mandrel F through the intervention of the rocking arm i' , the rock-shaft i^2 , to which that rocking arm is secured, the second rocking arm, i^3 , projecting from the rock-shaft, the slide arm, i^4 , which is operated by the second rocking arm, the sliding piston-rod i^5 , and the arm i^6 of the piston-rod, which last arm acts upon the end of the mandrel F. The arm i^6 of the piston-rod is fitted with an adjusting-screw, i^7 , so that the screw-die carried by the die-chuck E of the mandrel may be adjusted to its proper position relatively to the bolts to be operated upon. The piston i^5 is fitted with a spring, i^8 , to move the piston i^5 back to its starting position whenever the leading-cam permits such action. It is also expedient to apply a similar spring to the mandrel F to insure its removal from the point of the bolt after the screw-die has backed off thereof.
- 20 The time at which the leading-cam operates to do its work depends upon the time at which the mandrel is connected with the advancing clutch-wheel a^3 . Hence, if the latter time be varied, the former should vary with it. In order that the leading-cam may act in concert with the variation of the movement of the mandrel due to the action of the change gearing or mechanism before described, the leading-cam I is operated at intervals, succeeded 25 by intervals of rest. To this end the cam-shaft B⁴, that carries the leading-cam, is connected with the revolving driving-hub B³ (or some substitute therefor,) by means of a clutch, J, which is engaged with the driving-hub B³ when the leading-cam is to be driven, and is disengaged from the driving-hub when the leading-cam is to remain at rest. In order, moreover, that the same change mechanism which controls the reversing-clutch G may 30 also control the action of the leading-cam I, the clutch J, that connects the cam-shaft B⁴ with its driving-hub B³, is operated by a cam, K, secured to the change-gear shaft B⁵. This clutch-cam K operates upon the clutch-cam 35 through the intervention of the lever k, the rod k', and the clutch-fork k², which engages in a ring-groove of the clutch J. The clutch-cam K, in the present case, is arranged to disengage the clutch when the leading-cam is to 40 stop acting, and to permit the clutch to engage with the driving-hub J when the leading-cam is to commence acting, a spring, k³, being provided to move the clutch into engagement with the driving-hub whenever the clutch-cam K permits this operation.
- 45 If it is preferred that the gripping-jaws should advance the bolt-blank to the screw-die, the mandrel need not be constructed to slide endwise; but the standard which carries the gripping-jaws should be constructed to slide upon the frame, and should be connected with the leading-cam so as to be operated by it, this construction being an equivalent for that represented in the drawings.
- 50 In order that the bolt-blank to be screwed or threaded may be presented to the gripping-jaws D D automatically at the proper times, a magazine or bolt-holder, L, is provided to contain a supply of bolt-blanks, and mechanism is provided to take one bolt at a time from this bolt-holder and present it to the gripping-jaws D D, which hold the bolt-blank from revolving during threading. The bolt-holder L consists mainly of two slabs, l l, connected at their rear ends, with a space between them a little wider than the thickness of a bolt-stem, so that the bolt-blanks will lie horizontally in a column one above the other in said cavity, and will easily slip down the same when the lowest bolt is removed. The heads of the bolt-blanks protrude from the cavity, and are held in place by a head-piece, l', which, with two cheek-pieces, l² l², forms the connection of the side slabs of the bolt-holder at its head. The heads of the bolt-blanks are thicker than the stems thereof. Consequently the column of superimposed bolts assumes a curved form resembling the spokes of a wheel, and the head-piece l' and adjacent ends of the side slabs are curved correspondingly.
- 55 In order that the lowest bolt in the bolt-holder may be taken therefrom, the bolt-mover M is provided. This consists of two arms, m m, connected by a stock, m', with a rock-shaft, m², which is fitted to rock in bearings connected with the bolt-holder. The upper edges of the arms are curved concentrically with the rock-shaft for the greater part of their length, so that when their curved edges are beneath the cavity of the bolt-holder they act as a stop to prevent the escape of bolt-blanks. The ends of the arms m of the bolt-mover are notched sufficiently to admit the stem of a bolt-blank. Hence when these notches are brought under the cavity of the bolt-holder they will receive the lowest bolt-blank, and when the bolt-mover is subsequently moved by rocking its shaft m² this bolt-blank will be moved laterally from beneath the bolt-holder. While the bolt-blank is thus moved laterally it is prevented from turning axially in the bolt-mover by the guard l⁴, which is screwed to the side of the bolt-holder, with its lower edge projecting over the track in which the angular shoulder of the blank is carried by the bolt-mover. The blank is also prevented from changing its position longitudinally by means of a lateral projection, l⁵, of the head-piece l', and by the side of the guard l⁴, the said projection being at the outer side of the head of the bolt-blank, and the guard being arranged at its inner side or the shoulder thereof. The bolt-mover is operated at the proper times by means of a cam and a spring acting antagonistically. The cam N is secured to the cam-shaft B⁴, and operates upon the bolt-mover through the intervention of the arm n, the rock-shaft n', the second rocking arm, n², the connecting-rod n³, the arm n⁴, and the rock-shaft m², which, as before stated, is connected with the bolt-mover M. The cam, in the present case, is arranged to move the bolt-mover backward or

into the position to receive a bolt, while the spring is arranged to move the bolt-mover forward, or in such manner as to move the bolt laterally from beneath the bolt-holder. The 5 spring used for this purpose in the machine represented in the drawings is a helical spring, n^5 , Fig. 7, which is concealed in a tubular cavity of the rock-shaft n' , and operates by torsion upon the head of that rock-shaft.

10 In order that the whole column of bolts in the bolt-holder may not drop immediately when the notched ends of the bolt-mover are brought beneath the cavity of the bolt-holder, movable stops are provided. These stops are 15 by preference two in number, each consisting of a bar, O , which is constructed to slide crosswise of the cavity of the bolt-holder. The case or guide o of each stop is secured to the side of the bolt-holder, which also is perforated to permit the ends of the stops to enter the cavity beneath the lowest bolt but one. The stops O are provided with springs o' , which force them inward. They are withdrawn from beneath the column of bolts when 20 the latter are to be permitted to drop by means of arms o^2 , one for each stop, which operate upon studs protruding from the sides of the stops, and are connected with a rock-shaft, o^3 , which is supported in bearings connected with 25 the bolt-holder L . As these stops operate in concert with the bolt-mover, advantage is taken of this circumstance to withdraw them by connecting their rock-shaft o^3 with the rock-shaft m^2 of the bolt-mover by means of connecting-arms o^4 o^5 . Hence whenever the rock-shaft of the bolt-mover is operated to move the latter to the position for receiving the lowest bolt-blank in the bolt-holder the stops O are permitted to enter the cavity of the bolt- 30 mover and hold the other bolt-blanks from dropping; and whenever the bolt-mover has been moved laterally sufficiently to carry the lowest bolt from beneath the bolt-holder the stops O are withdrawn to permit the column of bolts to descend in the bolt-holder, so that the lowest bolt-blank is in the proper position to drop into the bolt-mover at its next 35 operation.

In order that the bolt-blank may be transferred from the bolt-mover to the jaws D D , the transfer-fingers P are provided. These fingers are connected with a vibrating arm, P' , the shank of one finger, p , Figs. 5 and 8, being connected rigidly with said arm, while 40 the shank of the other finger, p' , is pivoted to said arm, and is provided with a spring which tends to press the pivoted finger toward the rigid finger, the said spring being secured in the head p^2 of the arm P' . In order that these 45 fingers may seize the bolt-blank, the inner faces of their points have notches formed in them, one of which is V-formed, and the points of the fingers beyond these notches are slightly beveled or sloped outward, so that when the 50 fingers are pressed down endwise upon the shoulder of a bolt-blank lying in the bolt-mover these sloping points are caused to separate and admit the shoulder of the bolt-blank into the finger-notches, where it is held by the action of the finger-spring. In order that these 55 fingers may be moved endwise upon the bolt-blank, may transfer it to the gripping-jaws, and may return from those jaws, the fingers are moved by vibrating the finger-arm P' by the action of a cam and spring. The finger-cam Q is secured to the cam-shaft B^4 so as to be revolved by it, and operates upon the finger-arm P' through the arm P^2 and rock-shaft P^3 . The spring which operates automatically to 60 the cam Q is, in this example, the same torsion-spring, n^5 , Fig. 7, which operates upon the bolt-mover shaft n' , one end of said spring being connected with the end of the rock-shaft P^3 of the vibrating finger-arm through the intervention of a hub, P^4 . The object of making 65 the connection through the intervention of this hub is to enable the force of the spring to be adjusted by winding it up, and for this purpose the face of the hub P^4 is formed with ratchet-teeth, any one of which will engage 70 with a corresponding tooth formed upon the adjacent face of the hub of the rocking arm P^2 . Hence by turning the spring-hub P^4 the spring may be wound up and held in that condition by the engagement of one of its ratchet-teeth with the tooth of the finger-arm. The 75 periphery of the finger-cam is so formed as to raise the transfer-fingers high enough to permit the bolt-mover to move a bolt-blank laterally beneath their points, to let the fingers be depressed upon the bolt-blank so as to seize it, to hold the fingers at rest while the bolt-mover is withdrawn from the bolt seized by the fingers, and to permit the fingers to descend far enough to hold the bolt-blank in line 80 with the axis of the screw-die and the gripping-jaws.

The action of the finger-cam and spring thus far described is to move the bolt-blank to the axial line of the die and gripping-jaws D D . If 85 these jaws are so made and opened as to admit the head of the bolt when it is moved downward by the fingers, the bolt-blank, while being moved downward, may be introduced directly between the gripping-jaws; but it is 90 preferred to move the bolt-blank between the jaws by moving it endwise head foremost. In order that this movement may be effected the cam R is provided. This cam has upon one of its sides a grade which operates upon the 95 lower end of a lever, R' , which is pivoted to a standard of the main frame, and operates at its other end upon the shaft P^3 of the finger-arm P' . The action of the cam is to hold the finger-shaft from being moved endwise by the 100 endwise pressure of a spring, and the spring used for such endwise movement is the same spring n^5 which has before been described, and which, being compressed endwise between the head of the hollow rock-shaft n' and the 105 hub P^4 , tends to move that hub, the vibrating finger-arm P' with its fingers P , and the shaft 110

to which said arm is secured endwise in the proper direction to carry the fingers toward the griping-jaws.

The cam R is secured to the cam-shaft B⁴, which also carries the cams Q N, for controlling the operation of the transferring-fingers P and the bolt-mover M; and the grade of the cam R is so set relatively to the transfer finger-cam Q that when the transfer-fingers have, by their downward movement, carried the bolt to the axial line of the griping-jaws said fingers are permitted by the cam R to move sidewise toward the clamping-jaws N, so as to introduce the head of the bolt between them and hold the blank in this position until the jaws close upon its square shoulder. After the jaws have closed upon the bolt-blank the cam R moves the fingers sidewise away from the jaws to put them in the proper lateral position for a succeeding operation.

The cams N Q R, which thus control the movement of the bolt-blank to the clamping-jaws D D, are all secured to the cam-shaft B⁴, which carries the leading-cam I, so that the bolt-mover, stops, and transfer-fingers act in concert with each other and with the advance of the die-holder E. Moreover, as the operation of this cam-shaft is controlled by the variable-pawl change gearing or mechanism, as above described, the lengths of the intervals between the successive operations of feeding bolt-blanks can be changed to permit the threads to be cut a greater or less number of turns upon them.

When the machine is employed to cut the screw-threads of bolts which have angular shoulders, either square or polygonal, it is important that the bolt should be presented to the jaws with the corners of its angular shoulders in the proper positions to be grasped without bruising in corresponding angular notches of the said jaws. In order to insure this result the guard l⁴ at the side of the bolt-holder has its lower edge curved and set above the lower sides of the notches of the bolt-mover a distance slightly greater than the thickness of the angular shoulder of the bolt between its opposite sides. Hence the edge of this shoulder-guard l⁴ co-operates with the bolt-mover to form a species of channel and hold the bolt with the corners of its angular shoulder in the proper axial positions which they should have to be so presented by the transfer-fingers to the griping-jaws that the angles of the bolt-shoulder may correspond with the angles of the notches of the jaws. This shoulder-guard is also used in the machine, as before stated, to prevent the bolt from excessive longitudinal movement in the bolt-mover; but a separate guard may be used for that purpose.

In order that the bolt-blank may be moved by the transfer-fingers to its exact position axially of the spring-jaws and die, the spring n⁵ is employed to cause the descent of the

transfer-fingers, and a stop, S, is employed to limit their descending movement. An adjustable bumper, s, also is fitted to the finger-arm P', to strike the stop S, and the precise position at which the bolt is presented by the transfer-fingers can be determined by adjusting this bumper, or, if preferred, by using a fixed bumper and making the stop adjustable.

The die by which the threading or screwing is effected is, by preference, a solid die, and, as before stated, is carried by the die chuck or holder E, which is secured to the head of the revolving mandrel F. The solid die, if made according to the last part of my invention, is a block of steel of conoidal form, as represented at T, Figs. 12, 13, and 14, having upon its periphery several projections or teeth, t, which fit into corresponding notches formed in the cavity of the die-chuck E. The butt of this die is flat, so that it may set truly against the head f of the die-mandrel F, and the die is held there by the action of the die-chuck, which is composed of the screwed sleeve e, Fig. 12, and the screwed gland e', the first of which bears against the inner side of the mandrel-head and holds the gland e' and the die within it firmly in place. Dies of this construction are readily forged to the exact shape required by means of suitable forging-dies used in a drop-press, the cavity of the die conforming in form and size with the cavity of the die-chuck in which the die is to be used. The die is then drilled and cut while held in a die-chuck corresponding with that of the threading-machine, so that the die will fit the chuck of the threading-machine without any dressing up. Hence the cost of making dies for the screw-threading machine is reduced to a minimum. On the other hand, the die is free from any groove which requires a milling operation or a planing operation to form it, and which, by nicking the body of the die, renders it liable to crack in the hardening operation to which the die is necessarily subjected.

When the threading machine is to be put to work the variable-pawl change mechanism is adjusted according to the number of turns of screw-thread to be cut upon the bolts.

The bolt-blanks are put into the bolt-holder L by a child, and by the automatic operation of the machine the bolt-blanks are taken from the bolt-holder, one at a time, by the bolt-mover. The downward movement of the column of bolt-blanks in the bolt-holder is temporarily checked by the stops. The bolt-blank is presented for the action of the transfer-fingers, and is seized by them. The bolt-mover is withdrawn from beneath the bolt-blank, which is then transferred to the griping-jaws. These jaws seize the blank, the die advances upon it and cuts the thread to the required extent, the die backs off of the bolt by reason of the reversal of the movement of the mandrel, and the jaws are opened to permit the threaded bolt to drop. If the bolt hangs in the jaws it is knocked

downward from them by the downward movement of the next succeeding bolt-blank carried by the transfer-fingers.

The adjustment of the machine to the cutting of threads having a different number of turns is effected by changing the position of the adjustable crank-pin h^3 , as before described.

It is expedient that the time at which the feeding of the bolt commences relatively to the time of reversal of movement of the screw-die should be capable of being changed, and this capacity is given in the machine above described by constructing the cam-grade of the clutch-cam K of two parts, one of which is movable concentrically of the other, so that the grade, as a whole, may be lengthened or shortened in the direction of the periphery of the cam.

The movable part of the cam-grade is secured by a clamp-screw.

The speed at which the screw-die is advanced or pushed against the point of the bolt-stem should correspond with the pitch of the screw-thread to be formed.

In order that the same leading-cam I may be employed to advance the screw-dies for screw-threads of different pitches, the rocking arm i^3 is slotted, so that the pin i^6 , through which that arm operates upon the slide i^4 , can be set at greater or less distance from the rock-shaft i^2 , thus causing the slide and the mandrel and screw-die which are connected with that slide to be moved with greater or less speed by the same movement of the leading-cam I.

In order that the bolt-holder and the parts connected with it may be set to the proper positions to suit the bolts to be threaded, the standard U, which supports the bolt-holder, is constructed with a foot, u, which can be moved along the rest V, which supports it, and can be secured in any desired position by a screw-bolt.

For purposes of adjustment some of the rocking arms of the machine are constructed with split hubs, and are secured to their shafts by clamping the split hubs by clamp-screws. The ends of some of the arms also are slotted, so that the pins by which the arms are connected with other parts may have their positions changed.

The combination of the variable-pawl change-gearing with reversing-gearing, as above described by me, may be used with advantage in machines for other purposes than threading bolts.

I claim as my invention—

1. The combination, substantially as before set forth, of the change-gearing shaft and its cams, the ratchet-wheel, variable vibrating pawl, and adjustable crank-pin.

2. The combination, substantially as before set forth, of the clutch, shifting-pins, shifting-cam, pin-cams, cam-shaft of the change-gearing, ratchet-wheel, vibrating pawl, and adjustable crank-pin.

3. The combination, substantially as before set forth, of the jaws for holding the bolt-blank stationary, the revolving sliding mandrel, the bolt-holder, the bolt-mover, the transfer-fingers, and the variable-pawl change-gearing. 70

4. The combination, substantially as before set forth, of the transfer-fingers, finger-cam, finger-cam shaft, driving-hub, and clutch with the variable-pawl change-gearing. 75

5. The combination, substantially as before set forth, of the bolt-mover, bolt-mover cam, cam-shaft, driving-hub, and clutch with the variable-pawl change-gearing. 80

6. The combination, substantially as before set forth, of the bolt-holder, the bolt-mover, the stops for checking the descent of the bolts in the bolt-holder, and the transfer-fingers which take the bolt from the bolt-mover. 85

7. The combination, substantially as before set forth, of the gripping-jaws for holding the blank stationary, the bolt-holder, the bolt-mover, the transfer-fingers, arranged to move both endwise and sideways toward and from the gripping-jaws, and the variable-pawl change-gearing. 90

8. The combination, substantially as before set forth, of the bolt-holder, the bolt-mover, and the shoulder-guard, whose lower edge operates on the shoulder of the bolt while in the bolt-mover. 95

9. The combination, substantially as before set forth, of the bolt-mover, the shoulder-guard, and the transfer-fingers. 100

10. The combination, substantially as before set forth, of the bolt-holder and bolt-mover with a shoulder-guard whose edge operates on the shoulder of the blank while in the bolt-mover, and whose side is arranged in the proper position to operate on the inner side of the head of the bolt and prevent excessive longitudinal movement of the bolt. 105

11. The combination, substantially as before set forth, of the bolt-mover, the shoulder-guard, the transfer-fingers, and the gripping-jaws, to which the bolt is presented by the transfer-fingers. 110

12. The combination, substantially as before set forth, of the die-holder, the revolving sliding mandrel, the leading-cam, the slotted rocking arm, which enables the speed with which the die is advanced to be varied, and the variable-pawl change-gearing. 115

13. The combination, substantially as before set forth, of the conoidal screw-die with a die-chuck consisting of the screwed sleeve and screwed gland operating in connection with the mandrel-head. 120

Witness my hand this 11th day of February, A. D. 1879. 125
